UNITED STATES PATENT OFFICE.

DAVID C. BAUGHMAN, OF ALBION, INDIANA.

SELF-EXTINGUISHING LAMP.

SPECIFICATION forming part of Letters Patent No. 249,874, dated November 22, 1881.

Application filed September 13, 1881. (Model.)

To all whom it may concern:

Be it known that I, DAVID C. BAUGHMAN, of Albion, in the county of Noble, and in the State of Indiana, have invented certain new and useful 5 Improvements in Self-Extinguishing Lamps; and I do hereby declare that the following is a full, clear, and exact description thereof, reference being had to the accompanying drawings, and to the letters of reference marked 10 thereon, making a part of this specification.

This invention relates to certain improvements in that class of self or automatically extinguishing lamps in which the flame is extinguished at an appointed time by suitable 15 mechanism operated by means of a float in the oil-reservoir, which falls as the oil or burning fluid is consumed and throws or permits the extinguisher to fall over the wick.

The object of the present invention is to simplify 20 the construction of such extinguishers, to dispense with the use of springs, and provide a more efficient and reliable device for the purpose than heretofore. These objects I attain by the apparatus and devices illustrated 25 in the accompanying drawings, in which Figure 1 represents a side elevation of my improved lamp with a portion of the wall of the reservoir or fount broken away, showing the float therein. Fig. 2 represents a top view of the burner 30 and extinguishing devices, and Fig. 3 represents a detached view of one of the extinguishing-shields. Fig. 4 represents a detached view 35 of the burner, showing the extinguishing-wings fully separated, in which such wings are represented as curved, being a modification of my invention; and Fig. 5 indicates a vertical sectional view taken on the line $x-x$ of Fig. 1.

The letter A indicates the body or reservoir 40 of the lamp, which may be of the ordinary or any approved construction.

B indicates the burner, which is provided with the usual wick-tube, C.

The letter D indicates the cone or deflector, which is seated on the burner-cap in such position as to fall properly over the wick of the lamp, as usual.

The letters E E indicate two wings or shields, which are located one at each side of the wick-tube, and which are secured to the rods F F', 50 journaled in suitable bearings in the burner. The said rods at one side project beyond their

bearings and are bent at right angles, as shown in Fig. 4 of the drawings. The rod F from its horizontal bend is bent vertically downward, as indicated by the letter G, Fig. 3, the vertical portion being provided with a series of 55 graduations, H, for the purpose hereinafter described.

The letter I indicates a float located in the reservoir of the lamp and attached to a rod, I', 60 extending through a packed opening, K, at the top of the lamp. The said rod is beveled at its upper end, and is adapted to bear against the vertical portion of the rod F, so as to separate the shields and hold them away from the 65 wick-tube while the lamp is burning. The bent arm of the rod F' lies in conjunction with the horizontal portion of the rod F, so that the two shields will be operated simultaneously.

The letter H' indicates a lateral lug on the 70 end of the rod I', which prevents the rod from dropping through the opening K when the float falls.

The letter M indicates a stop secured to the 75 top of the lamp, which is adapted to engage the wick-raising shaft and arrest the burner at the proper point, when screwed home, to bring the rods F and I' in proper conjunction.

The float is oblong in shape, and is located 80 in a chamber formed by a suitable partition in the lamp, which prevents said float from turning, thus holding the rod I' in proper position.

Having thus described my invention, what I claim, and desire to secure by Letters Patent, is—

In combination with the burner and wick-tube of a lamp, the wings or shields secured 85 to the pivoted rods having their ends bent, as described, one of said rods being provided with a vertical graduated extension and the float 90 and its stem, the latter being adapted, when elevated, to engage the graduated portion of the rod operating the shields, substantially as and for the purposes specified.

In testimony that I claim the foregoing I 95 have hereunto set my hand this 5th day of September, 1881.

D. C. BAUGHMAN.

Witnesses:

JOHN M. CHAPMAN,
L. W. WELKER.
